UNITED STATES PATENT OFFICE.

DANIEL SCHUYLER, OF LOS ANGELES, CALIFORNIA, ASSIGNOR TO THE PERFECT SLIDING DOOR COMPANY, OF LOS ANGELES, CALIFORNIA, A CORPORATION OF CALIFORNIA.

FASTENER FOR EDGEWISE-MOVING CLOSURES.

No. 867,587.

Specification of Letters Patent.

Patented Oct. 1, 1907.

Application filed December 14, 1900. Serial No. 39,893.

To all whom it may concern:

Be it known that I, DANIEL SCHUYLER, a citizen of the United States, residing at Los Angeles, in the county of Los Angeles and State of California, have invented new and useful Fasteners for Edgewise-Moving Closures, of which the following is a specification.

An object of my invention is to provide a cheap, superior, neat, sightly, secure and convenient device by means of which an edgewise-moving closure for a door, window, or the like, can be positively locked partly open, the fastener being readily operated from the inside of the door, but proof against unfastening from the outside, the catch and all other parts of the fastening device, except the handle being nonaccessible and concealed from view. The fastener is also adapted for fastening the closure when completely closed, and also for fastening the closure at different points to leave an opening of a greater or less width at the edge of the door, up to the limits of safety, thus providing for means of ventilation through the opening without danger of intrusion.

An object of my invention is extreme simplicity, and economy of time, labor and material in constructing and installing the device.

Another object is to so construct the appliance that it is interchangeable to be used at either the right or the left edge of the door.

Another object is to provide a keyless flush-fastener which when unfastened will not project from the sides of the closure, thus allowing the closure to freely slide in a close-fitting pocket.

My invention comprises the combination of a stationary part furnished with an opening and with a pocket at the edge of the opening; an edgewise moving part forming a closure for said opening and constructed and arranged to move into said pocket; a catch; a fastening-bolt forming a part to positively engage the catch; and a rock-shaft operatively connected with the bolt to move the same into and out of engagement with the catch; the shaft being furnished with means for partial rotation thereof for engaging the bolt with and disengaging it from the catch; the catch being fastened to one of said parts and the shaft and bolt being on the other part. This may be variously arranged and constructed, and in the accompanying drawings I have shown the form which I at present believe to be preferable for general application.

The accompanying drawings illustrate the invention. Figure I is a view of my invention applied to a door. A portion of the door-frame is broken away to expose the adjustable stationary catch. Fig. II is an enlarged sectional detail on line II-II, Fig. I. Fig. III is a view from line III-III, Fig. II, looking to the right. Fig. IV is a section on line IV-IV, Figs. I and II, look-

ing to the right. Fig. V is a view of the handle of the fastener in place. A fragment of the door is shown. Fig. VI is a view of the adjustable catch fastened to the door-post at one side of the mouth of the pocket which receives the door. Fig. VII is a section on line VII-VII, Fig. III, the fastening arm being shown intact. Fig. VIII is a sectional detail of the fastening for the lock-retaining spring.

a is a door-frame furnished with an opening b and with a pocket c at one side of the opening.

d is an edgewise moving, sliding member, being a disappearing closure for the opening and adapted to enter the pocket c. Said closure slides in the opening b and pocket c.

e is a stationary adjustable catch-plate or keeper at one side of the opening, the same being fastened on the inner face of the door-post f at the mouth of the pocket c.

g indicates a rock-shaft journaled in the closure and furnished with a handle h, and at a distance from the handle, furnished with a bolt in the form of an arm i to be brought into engagement with the catch-plate e 75 and to be disengaged therefrom by the partial rotation of the shaft. The arm i and the handle h are so arranged that both will chamber between the sides of the door when the handle is thrown down into the position indicated by the lower dotted lines in Fig. IV; and the fastening-arm i is arranged with such relation to the handle h that when the handle is thrown into its uppermost position, the arm i will project beyond the plane of the door, while the handle h is chambered inside the plane of the door. 85

The shaft g is rigidly fixed to the locking-arm i and is journaled in a hole j bored inward from the edge k of the closure, for that purpose. The shaft g is furnished with one or more handle-receiving holes m and into which the handle h may be suitably fastened. 90 Preferably, the holes m and the handle h are screw-threaded, and where two holes are provided, they will be set at right angles to each other crosswise of the shaft and with definite relation to the position of the locking-arm i on the other end of the shaft, so that 95 when the fastener is to be used for one side of the door the handle h will be screwed into one of the holes m, and vice versa for the other side of the door.

The handle h and the locking-arm i are preferably set quartering with each other on the shaft, so that 100 when the arm projects at right angles to the face of the closure to lock in the catch-plate e, the handle h will project upward at an angle of forty-five degrees. The length of the handle is such that when the handle is in its uppermost position it is completely chambered 105 within the closure. When the handle is thrown down to unlock the fastener, it is again chambered inside the closure, as indicated in dotted lines in Figs. III and IV.

o indicates a handle-socket let into the closure and furnished with a vertical slot *p* in which the handle *h* plays.

q indicates a handle-retaining spring mounted at the back of the socket *o* and bent to project into the path of the arm *h* and being bowed at the middle to prevent the handle from moving in either direction except under applied pressure, thus preventing any rattling, and also avoiding any danger of the fastener moving out of its locked or unlocked position except when the handle is intentionally moved by applied pressure.

The handle *h* is remote from the edge of the closure that is farthest from the pocket, so as to be inaccessible to a person on the outside of the closure and who might pass his arm or an instrument through the opening around such edge and attempt to reach the handle.

Preferably, the spring is a bow-spring fastened at its ends to the socket-plate *o*. Preferably the socket-plate is made of thin sheet-metal or other suitable sheet material, and two holes *r r'* are punched at the appropriate points on the mid-line of the socket-plate near the ends thereof by a punch which does not remove the metal, but will press it backward to form projecting tubed eyelets *13*; and the ends of the spring are furnished with loops *t* to encircle the projecting tubes of the eyelets which are then swaged down over the loops, thus fastening the spring firmly to the back of the socket-plate.

u indicates screws inserted through the eyelet-holes and screwed into the body of the closure *d* to hold the socket-plate in place.

In order to prevent the fastener from being manipulated by means of a thin blade or other instrument inserted between the closure and the catch-plate *e* to press upon the arm *i*, said arm is furnished with a broad portion formed with oblique shoulders *1, 2*, at the opposite sides respectively of the locking-projection *3* of said arm. The shoulder *1* slants to the locking-projection *3* from a radius of the locking-arm which is greater than the distance between the catch-plate *e* and the axis of the shaft, so that as the locking-arm is turned to bring the locking-projection away from the catch plate, the shoulder will shear toward the plate and will thus grip any instrument which might be inserted for the purpose of pressing the locking-projection downward. The shoulder *2* is slanted in like manner so that when the fastener is reversed the same action will be maintained.

v indicates tacks or other suitable markings on the face of the closure to indicate to the operator the points at which the locking-arm will enter the slots *7* of the catch-plate, said slots constituting retaining means for the plate.

w and *x* indicate two retaining-plates for the shaft *g* and the locking-arm *i*. The retaining-plate *w* is furnished with a perforation *5* registering with the hole *j* in the sliding member *d* and with perforations *5'* for the fastening-screws *g*. The other retaining-plate *x* is furnished with like perforations *5''*. The plate *w* is also furnished with bosses *6* raised around the fastening perforations to space the plates apart so that they will chamber the locking-arm *i*.

7 indicates slots at intervals in the plate *e* into which the locking-arm *i* will seat to lock the closure in the appropriate position.

8 indicates guide-plates to fit over the opposite edges of the slotted-plate *e*. These guide-plates are fastened to the support *f* by suitable means, such as the tacks *9*. The catch-plate *e* preferably is bent to form a projecting body *10* between two straight-edge flanges *11*, which body *10* is furnished with the slots *7* extending transversely thereof. The guide-plates are bent to fit upon the support *f* and over the flanges *11*.

In practice, in mounting the catch, the guide-plates *8* will be fastened in appropriate position at the desired height to bring the slots into position to receive the locking-arm *i*. Then the catch-plate will be inserted between the guide-plates and will be slid to the appropriate position and then fastened relative to the support *f* with the screws *12* screwed into the support *f*.

To lock the closure, the operator will take hold of the handle with one hand and with the other hand will slide the closure, at the same time drawing the handle out to bring the locking-arm against the smooth face of the catch-plate *e* along which the arm will slide until it comes to one of the slots which it will immediately enter. The operator will then throw the handle *h* up into its uppermost position and the spring *q* will retain it in that position, thus preventing it from being jarred by any shaking of the closure. In thus fastening the closure, the operator will not throw the arm until the door is approximately in the position in which it is desired to lock it, and the closure can thus be secured completely closed or partly open; the limit of the opening which can thus be left with security being governed by the number and position of the slots in the catch-plate. An opening can thus be left with practical security, which will be large enough to admit the hand and arm of a person, and if any attempt is made to apply an instrument against the locking-arm to force it down, when such arm moves downward the slanting shoulder will immediately grip the instrument and prevent any further downward movement of the arm. The slanting portion of the shoulder is of sufficient length to extend completely across the space between the face of the closure and the catch-plate, so that there will be no projection of the locking-arm which can be positively engaged by an instrument to force it down.

The handle *h* is fully chambered within the recess therefor when the door is locked, so that the would-be intruder is unable to manipulate the handle with any ordinary instrument. Any attempt to unlock the closure will be apparent to the inmate of the room and therefore involved in more danger than the ordinary picking of a fastener from the outside.

It is to be understood that I do not propose to limit myself to the particular form of means for locking the closure which I have shown in the drawings and which comprise the bolt *i* and the catch-plate *e* with which it is engaged.

What I claim and desire to secure by Letters-Patent of the United States is:—

1. The combination of a frame furnished with an opening and with a pocket; an edgewise moving closure for the opening, said closure adapted and arranged to enter the pocket; a stationary keeper at one side of the opening and within the pocket; a shaft journaled in the closure and extending along the path of said closure and furnished with a handle, and at a distance from the handle with an arm inside the pocket to be brought into

engagement with the keeper and to be disengaged therefrom by the partial rotation of the shaft.

2. The combination of a stationary catch-member furnished at intervals with slots; a member to slide along side said stationary member; a shaft journaled in the sliding member and extending through a portion of the sliding member and in the direction of movement thereof and furnished with an arm to enter the respective slots of the stationary member, and also furnished with a handle extending through a portion of the sliding member by which the shaft can be partially rotated to throw the arm into and out of the slots.

3. The combination of an edgewise moving member furnished with a hole extending into its edge in the direction of movement thereof, and with a recess communicating with the inner end of said hole; a shaft furnished at one end with a laterally-projecting arm and having its other end inserted into the hole and brought opposite the recess, and provided opposite the recess with a screw-threaded hole; and a handle fastened to said shaft and extending into said recess and engaging in said screw-threaded hole, for the partial rotation of the shaft.

4. The combination of an edgewise-moving member furnished with a hole extending in the direction of movement of said member, from one edge toward the other edge thereof, and with a recess communicating with the inner end of said hole; a shaft furnished at one end with a laterally-projecting arm and having its other end inserted into the hole and brought opposite the recess; a handle fastened to said shaft and extending into said recess for the partial rotation of the shaft; and a retaining-plate fastened to said member and extending over the arm.

5. In a device of the character described, a shaft adapted to be mounted in a hole on a sliding closure provided at one end with a projecting arm, and at a distance from said arm with two perforations extending at different angles to the arm; and a handle for insertion into either of said perforations.

6. The combination of an edgewise-moving member furnished with a hole extending into the member from one edge thereof, and a recess opening into the side of the member and communicating with the hole; a shaft journaled in the hole and furnished at one end with a projecting arm and furnished with a perforation at the other end; a socket member seated in the recess and furnished with a slot to register with the perforation in the shaft; a handle extending through the slot and fastened in the perforation; and a spring to engage the handle and to forcibly press against the same.

50 7. In a fastener for doorways, the combination of a stationary keeper; a sliding member; a shaft journaled in said member and extending in the direction of movement thereof; means for turning the shaft; and an arm fastened to the shaft and projecting beyond the side of the member and provided with a broad portion which at one position of the shaft will project slightly beyond the face of the sliding member, and a narrow portion extending beyond the broad portion, said arm being arranged to be wholly withdrawn from its projecting position when the shaft is rotated into the appropriate position for that purpose.

8. In a fastener, the combination of a slotted socket-plate furnished with projecting eyelet-tubes; a spring bowed to extend across a portion of the slot and furnished at its ends with loops around the eyelet-tubes and fastened to said tubes.

9. The combination of a stationary keeper, a sliding member, a shaft journaled to the sliding member, means for partially rotating the shaft, and a locking-arm on the shaft furnished with a projection to engage the catch at one position of the shaft and to be disengaged from the catch at another position of the shaft, and also furnished

with a sloping shoulder to shear across the opening between the sliding member and the catch as the locking-arm is moved to withdraw it from its fully-locked position.

10. In a fastener for doorways and the like, the combination of a stationary keeper at one side of the doorway, a sliding closure for such doorway furnished with a hole extending from one edge toward the other edge and with a recess communicating with said hole; a plate applied to the edge of the sliding closure and furnished with a perforation registering with said hole and with perforations for fastening-screws; a shaft journaled in said hole and the perforation registering therewith and furnished with a locking-arm engaging said plate and with a handle extending into said recess; a plate mounted outside said arm, furnished with perforations registering with said fastening-perforations, one of said plates being furnished around its fastening-perforations with bosses to space the plates apart to chamber the locking-arm between them, and screws inserted through the perforations of said plates and screwed into the edge of the closure.

11. The combination of a stationary part furnished with an opening and with a pocket at one edge of the opening; an edgewise moving part forming a closure for said opening; a keeper; a locking-arm for engagement with the keeper; and a rock-shaft operatively connected with the locking-arm to move the same into and out of engagement with the keeper; said rock-shaft being furnished with means for partial rotation thereof for engaging the locking-arm with and disengaging it from the keeper, the keeper being fastened to one of said parts and the shaft and locking-arm being on the other of said parts.

12. The combination of an edgewise moving member furnished with a hole extending into the member from one edge thereof and a recess opening into the side of the member and communicating with the hole; a shaft journaled in the hole and furnished at one end with a projecting arm and furnished with a handle in the recess; and a spring to prevent rotation of the shaft except under applied pressure.

13. The combination of a wall provided with a pocket; a disappearing edgewise moving closure arranged to move into and out of the pocket; a part on the closure and a part permanently in the pocket adapted to positively engage with each other and constructed and arranged to prevent the edgewise movement of the closure by application of force; said part on the closure being provided with a handle that enters the pocket when the closure is open.

14. The combination of a wall provided with a pocket; a disappearing edgewise moving closure arranged to move into and out of the pocket; a catch plate on the closure and a part permanently in the pocket, the same being provided with a plurality of slots adapted to positively engage the closure to lock the closure at several positions along its path against movement by application of force.

15. The combination of a frame having an opening and a pocket at one edge of the opening, a keeper in said pocket having a plurality of retaining means located at different distances from the opening, a closure moving edgewise in the opening and pocket, and a shaft mounted in said closure in the direction of the edgewise movement and provided with an arm to engage the aforesaid retaining means, and with a handle for partial rotation of the shaft.

In testimony whereof I have signed my name to this specification in the presence of two subscribing witnesses, at Los Angeles, California, this 8th day of December, 1900.

DANIEL SCHUYLER.
